CATHODE RAY SWEEP CIRCUITS

Frank R. Norton, Livingston, N. J., assignor to
 Bell Telephone Laboratories, Incorporated,
 New York, N. Y., a corporation of New York

Application February 25, 1936, Serial No. 65,607

13 Claims. (Cl. 250—36)

This application relates to cathode ray devices
 cuits suitable for television scanning and for gen-
 and more specifically to cathode ray sweep cir-
 cular oscillographic purposes.

5 In order to produce proper linear scanning in
 cathode ray tubes, it is necessary to have sweep
 circuits capable of generating saw-tooth wave
 forms. To produce wave forms of this general
 shape, circuits in the prior art have been devised
 10 which charge up a condenser through a resistance
 or through a saturated diode, the condenser being
 discharged at suitable intervals by a suitable gas-
 filled electron discharge device such as a "Thyra-
 tron" tube actuated by received synchronizing
 15 signals or by an oscillator. The wave forms pro-
 duced by these circuits have deviations from the
 exact saw-tooth wave form desired because of
 the fact that neither the resistance nor the diode
 at saturation produces a constant plate current
 20 with changes in plate voltage.

20 It is an object of this invention to provide im-
 proved television scanning means.

It is another object of this invention to pro-
 vide means for producing an improved saw-
 tooth wave form adapted for use in a sweep cir-
 25 cuit.

It is a further object of this invention to provide
 improved means for maintaining the current in
 a circuit substantially constant under varying
 30 impressed voltages.

30 In carrying these objects into effect, there is
 preferably employed a pentode tube in series with
 a battery to charge up a condenser or condensers
 in a sweep circuit, these being discharged by the
 35 periodic discharge of a "Thyatron" tube actuated
 by synchronizing signals. Preferably, the
 pentode tube is connected so that the current in
 the output circuit of the tube controls the bias
 on either the control grid, the screen grid, the
 40 suppressor grid, or any combination of these
 three. It has been found that the pentode gives
 a flatter plate current versus plate voltage char-
 acteristic than a triode and for this reason is
 preferred. A triode or a tetrode with a feedback
 45 connection to a grid or grids may be used but it
 has been found that the pentode type of tube
 with feedback on one or more of its grids is par-
 ticularly effective. If the feedback is to be to a
 single grid, the control grid is preferred. Some-
 50 what better results are obtained by including also
 the screen grid or suppressor grid, or both, in the
 feedback connection. By means of this arrange-
 ment of connections, as the plate voltage de-
 creases, the bias on one or more of the grids is
 55 reduced and hence the current tends to remain

constant. With this "feedback" hook-up, the
 pentode tube tends to give a very stable output
 current regardless of voltage changes. The re-
 sultant sweep circuit voltage is thus of the de-
 sired saw-tooth wave form to produce correct 5
 linear scanning.

The invention will be more readily understood
 from the following description taken in connec-
 tion with the accompanying drawing forming a
 part thereof in which:

Fig. 1 shows a sweep circuit for producing saw-
 tooth wave forms;

Figs. 2 and 3 show modifications of the hook-up
 for the pentode tube shown in Fig. 1; and

Figs. 4 and 5 are graphic representations in- 15
 cluded to better explain the operation of this in-
 vention.

Referring more particularly to the drawing,
 Fig. 1 shows a sweep circuit for a cathode ray
 oscilloscope tube in which a pentode tube 10 is 20
 used. The circuit comprises a means such as
 battery 11 for charging condensers 12 and 13
 through the pentode tube 10, and a "Thyatron" 25
 tube 14 for discharging these condensers at pre-
 determined periodic intervals, these discharges 25
 being actuated by synchronizing signals. A suit-
 able source of synchronizing signals, represented
 generally by the box 15, may comprise, for ex-
 ample, a receiver for receiving these signals from
 a transmitting station or it may be a local oscil- 30
 lator at the station where the sweep circuits are
 located. The source 15 is coupled by means of a
 transformer 16 and resistances 17 and 18 to the
 grid 19 of the "Thyatron" tube 14. The grid is
 normally negatively biased by the battery 20 lo- 35
 cated between the cathode 21 and the grid 19
 of the "Thyatron" tube. In the plate circuit of
 the "Thyatron" tube 14 is a resistance 22 and one
 set of sweep plates 23 and 24 of a cathode ray
 device. 40

The voltage applied across the sweep plates 23
 and 24 is determined by the charging and dis-
 charging of the condensers 12 and 13 and the
 voltage wave form follows the general form of
 the full line wave shape 50 shown in Fig. 4. The 45
 condensers 12 and 13 may be, if desired, replaced
 by a single condenser. In the preferred em-
 bodiment of this invention, however, two con-
 densers in series are used with their common
 terminal connected to a point of fixed potential 50
 in order to produce a balanced sweep circuit.
 The potentials generated by the sweep circuit may
 be balanced with respect to the potential of the
 accelerating anode 45 of the cathode ray tube by
 using coupling condensers 43 and coupling resistor 55

44. For a more complete description of balanced sweep circuits, in general, reference should be made to an application filed February 25, 1936 Serial No. 65,606, by Frank Gray.
- 5 The elements of the pentode tube 10 and the connections therefor will now be described. This tube comprises a cathode 25, a heater element 26 for the cathode, a plate or anode member 27, a control grid 28, a screen grid 29 and a suppressor grid 30. Current for the heater element 26 is supplied by any suitable means such as the secondary 31 of a transformer, the mid-point of this secondary being connected to the cathode 25. A battery 32 places the screen grid 29 at a positive potential with respect to the cathode, preferably at a potential between that of the cathode 25 and the plate 27. The suppressor grid 30 is connected to the cathode 25 and this connection may be, as desired, made either in the tube envelope or externally. Bias is supplied to the control grid 28 of the tube 10 by means of the resistance 33 which may be, if desired, variable. This biasing resistance 33 serves a double purpose. First, it takes the place of a biasing battery, and second, as it is in the circuit including the battery 11, condensers 12 and 13 and the plate circuit of the device 10, it serves to change the bias on the control grid 28 as the current in the external circuit changes. If desired, a battery may be included in the circuit including the cathode and the resistance 33 to produce a fixed bias. Thus, it can be said that there is a "feedback" from the plate circuit to the grid circuit of the device 10. Its function will now be considered.
- 35 In order to better explain the operation of the device 10, reference will now be made to Figs. 4 and 5. In Fig. 5, curve 40 represents a typical plate current versus plate voltage characteristic of a diode tube which has been customarily used in cathode ray sweep circuits of the past. It will be noted that while the curve tends to flatten out as higher voltage values are reached, it is still not very close to the ideal constant current characteristic desired. The ideal characteristic is represented by the dotted line 41. In the ideal sweep circuit, the current in the condenser charging circuit must remain constant even with changes in voltage if the rate of charge with respect to time is to remain linear. In order to bring this out more fully, the operation of the sweep circuit will now be described.
- 55 The battery 11 charges the condensers 12 and 13 in series through the device 10. As the potential between points A and B rises as the condensers are charged, the potential drop across the tube 10 falls because the battery 11 supplying the electromotive force for this series circuit tends to produce a substantially constant potential. This drop across the device 10, assuming that it is an ordinary resistance or a diode, would cause a decrease in the current in the circuit which would tend to charge the condensers at a slower rate. The dotted curve 51 of Fig. 4 illustrates the effect of this decrease in the charging rate. This departure from linearity in the saw-tooth wave form will cause distortion of the image on the fluorescent screen of the cathode ray tube. The use of the pentode in place of the diode will materially improve the linearity of the wave form as pentodes have an inherently flatter plate current versus plate voltage characteristic. In Fig. 5 the curve 42 represents the characteristic of an ordinary pentode tube (without feedback). If the pentode is connected as shown in Fig. 1, the characteristic tends to approach the ideal char-

acteristic curve 41. This is true because any decrease in plate current will decrease the potential drop across the biasing resistance 33, thus decreasing the control grid bias and allowing a greater flow of current. The current through the tube 10 and through the circuit including the series condensers 12 and 13 thus tends to remain substantially constant and the condensers are charged at a uniform rate with respect to time, the resultant wave form tending to approach the ideal saw-tooth form 50, shown in full lines in Fig. 4.

When the charge across the condensers has been allowed to build up during the desired time interval, the condensers are discharged, this discharge producing the "fly-back" of the cathode ray beam. Let it be assumed, for example, that the sweep circuit of Fig. 1 is to be used to produce horizontal deflection of the beam. At the end of each line of the picture, a synchronizing signal 15 will cause the "Thyratron" tube 14 to be discharged and the electron beam will fly back to place itself in position to scan the next line. The condensers will then begin to charge again and the entire cycle will be repeated over and over again at a frequency depending upon the frequency of the synchronizing signals generated by the source 15. Once every cycle, therefore, the source 15 supplies a signal which overcomes the negative bias of the "Thyratron" tube 14 to cause a discharge to be initiated which in turn causes the condensers 12 and 13 to be discharged through the resistance 22 and the discharge path of the "Thyratron" 14. When the potential between plate and cathode of the "Thyratron" tube drops to a low value due to the discharge of the condensers, the discharge current stops and the grid 19 regains control of the "Thyratron" and thus is in a position to initiate the next discharge at the proper time.

The change in potential between the points A and B may be impressed between the deflecting plates 23 and 24 of a cathode ray tube by any desirable means such as, for example, by coupling condensers 43 and resistance 44, the mid-point of which resistance is preferably connected to the accelerating anode 45 of the cathode ray tube.

To produce vertical deflection, a circuit similar to that of Fig. 1 would be used. The frequency of the wave form produced by this circuit would, of course, be much smaller than that of the circuit producing horizontal deflection, as in television the frequency of the deflections produced by this circuit bears to that of the circuit producing horizontal deflection some definite ratio, and the circuit constants would therefore be different. Aside from these differences, however, the description and operation described above in connection with the horizontal sweep circuit apply equally as well to a circuit for producing vertical deflection. The above description applies to the case where horizontal scanning is used. It is obvious, however, that the sweep circuits may be reversed and vertical scanning used instead.

Figs. 2 and 3 show modifications of the method of connecting the elements of the pentode tube 10, shown in Fig. 1. Either of the hook-ups shown in Figs. 2 and 3 may be substituted for the portion of Fig. 1 below the line X-X. In both Fig. 2 and Fig. 3 the pentode tube 10 contains exactly the same elements as the tube used in Fig. 1, but the external connections are slightly modified.

In Fig. 2, the screen grid instead of being at a fixed potential with respect to the cathode 25 (as in Fig. 1) is arranged by means of a battery 46

connected between the screen grid 29 and the biasing resistance 33 to give feedback on the screen grid as well as on the control grid 28. The effect of having feedback on both the control grid 28 and the screen grid 29 is cumulative and tends to produce a characteristic very close to the ideal characteristic 41.

Fig. 3 differs from Fig. 2 in that feedback is applied to the suppressor grid 30 as well as to the control grid 28 and the screen grid 29. This feedback is obtained by connecting suppressor grid 30 to the terminal of the biasing resistor 33 remote from the cathode connection to this resistance. If desired, a source of fixed potential 10 may also be inserted in this circuit. By means of this method of connecting the three grids 28, 29 and 30, the current through the resistance 33 changes the bias on the three grids 28, 29 and 30 with respect to the cathode 25 and has the effect 15 of keeping the current through the tube substantially constant.

It will be obvious that other combinations may be used as well as those above described and that this invention in certain aspects may be carried 20 out with any electron discharge tube arrangement.

Various other modifications may be made without departing from the spirit of the invention, the scope of the invention being defined by the appended claims.

What is claimed is:

1. A linear time axis generator comprising two condensers connected in series with their common terminal placed at a fixed potential, means 35 comprising a pentode electron discharge device and a source of direct current for charging said condensers at a substantially uniform rate, and means for periodically discharging said condensers simultaneously.

2. A sweep circuit for a cathode ray tube comprising two condensers connected in series with their common terminal placed at a fixed potential, an electron discharge device, having at least one grid, connected in circuit with said condensers, and means for controlling the bias of said 45 grid in accordance with the current through said device.

3. An electron discharge device arrangement for use in cathode ray sweep circuits comprising an electron discharge device having a cathode, 50 an anode, a control grid, a screen grid, and a suppressor grid, two condensers connected in a series circuit with said cathode and anode with the common terminal of said condensers placed at a fixed potential, means for producing a flow 55 of current between said cathode and anode, and means including apparatus responsive to said flow of current and which controls the biasing potential between said cathode and said suppressor grid for controlling said flow of current in such a manner that it tends to remain substantially constant in intensity.

4. An electron discharge device arrangement for use in cathode ray sweep circuits comprising 65 an electron discharge device having a cathode, an anode, a control grid, a screen grid, and a suppressor grid, two condensers connected in a series circuit with said cathode and anode with the common terminal of said condensers placed 70 at a fixed potential, means for producing a flow of current between said cathode and anode, and means including apparatus responsive to said flow of current and which controls the biasing potential between said cathode and at least two 75 of said grids for controlling said flow of current

in such a manner that it tends to remain substantially constant in intensity.

5. An electron discharge device arrangement for use in cathode ray sweep circuits comprising an electron discharge device having a cathode, 5 an anode, a control grid, and a screen grid, two condensers connected in a series circuit with said cathode and anode with the common terminal of said condensers placed at a fixed potential, means for producing a flow of current between said cathode and anode, and means including apparatus responsive to said flow of current and which controls the biasing potential between said cathode and said control and screen grids for controlling said flow of current 10 in such a manner that it tends to remain substantially constant in intensity.

6. An electron discharge device arrangement for use in cathode ray sweep circuits comprising an electron discharge device having a cathode, 20 an anode, a control grid, a screen grid, and a suppressor grid, two condensers connected in a series circuit with said cathode and anode with a common terminal of said condensers placed at a fixed potential, means for producing a flow of current 25 between said cathode and anode, and means including apparatus responsive to said flow of current and which controls the biasing potential between said cathode and said control and suppressor grids for controlling said flow of current 30 in such a manner that it tends to remain substantially constant in intensity.

7. An electron discharge device arrangement for use in cathode ray sweep circuits comprising an electron discharge device having a cathode, 35 an anode, a control grid, a screen grid, and a suppressor grid, two condensers connected in a series circuit with said cathode and anode with the common terminal of said condensers placed at a fixed potential, means for producing a flow of 40 current between said cathode and anode, and means including apparatus responsive to said flow of current and which controls the biasing potential between said cathode and said suppressor and screen grids for controlling said flow 45 of current in such a manner that it tends to remain substantially constant in intensity.

8. An electron discharge device arrangement for use in cathode ray sweep circuits comprising an electron discharge device having a cathode, 50 an anode, a control grid, a screen grid, and a suppressor grid, two condensers connected in a series circuit with said cathode and anode with the common terminal of said condensers placed at a fixed potential, means for producing a flow 55 of current between said cathode and anode, and means including apparatus responsive to said flow of current and which controls the biasing potential between said cathode and all three of said 60 grids for controlling said flow of current in such a manner that it tends to remain substantially constant in intensity.

9. A linear time axis generator comprising two condensers connected in series with the common terminal of said condensers placed at a fixed potential, means including a constant current device and a direct current source in series with said condensers for charging said condensers, said constant current device comprising an electron discharge device having a cathode, an anode, a 70 control grid, a screen grid, and a suppressor grid, means including said direct current source for maintaining a flow of current in said discharge device, and means including a resistance in circuit between said cathode and one or more of 75

said grids to control the bias on at least one of said grids to thereby keep the flow of current through said device substantially constant, a gas-filled electron discharge device having an input 5 and an output circuit, said output circuit including said condensers, and signal responsive means for periodically starting a discharge in said gas-filled discharge device to thereby discharge said condensers.

10 10. A linear time axis generator comprising two condensers connected in series with the common terminal of said condensers placed at a fixed potential, means including a constant current device and a direct current source in series with 15 said condensers for charging said condensers, said constant current device comprising an electron discharge device having a cathode, an anode, a control grid, a screen grid, and a suppressor grid, means including said direct current 20 source for maintaining a flow of current in said discharge device, means including a resistance in circuit between said cathode and said control grid to control the bias on said grid to thereby keep the flow of current through said device substantially 25 constant, a gas-filled electron discharge device having an input and an output circuit, said output circuit including said condensers, and signal responsive means for periodically starting a discharge in said gas-filled discharge device to thereby discharge said condensers.

11. A linear time axis generator comprising two condensers connected in series with the common terminal of said condensers placed at a fixed potential, means including a constant current 35 device and a direct current source in series with said condensers for charging said condensers, said constant current device comprising an electron discharge device having a cathode, an anode, a control grid, a screen grid, and a suppressor grid, means for fixing the biasing potentials of said 40 control and suppressor grids with respect to said cathode, means including said direct current source for maintaining a flow of current in said discharge device, means including a resistance in circuit between said cathode and said control grid to control the bias on said grid to thereby 45 keep the flow of current through said device substantially constant, a gas-filled electron discharge device having an input and an output circuit, said output circuit including said condensers, and signal responsive means for periodically 50 starting a discharge in said gas-filled discharge device to thereby discharge said condensers.

charge device to thereby discharge said condensers.

12. A linear time axis generator comprising two condensers connected in series with the common terminal of said condensers placed at a fixed potential, means including a constant current device and a direct current source in series with 5 said condensers for charging said condensers, said constant current device comprising an electron discharge device having a cathode, an anode, a control grid, a screen grid, and a suppressor grid, means for fixing the biasing potential of said suppressor grid with respect to said cathode, means for fixing the biasing potential of said screen grid with respect to said control grid, means including said direct current source for maintaining a flow of current in said discharge device, means including a resistance in circuit between said cathode and said control grid to control the bias on said grid to thereby keep the flow of current through said device substantially constant, a gas-filled electron discharge device having an input and output circuit, said output circuit including said condensers, and signal responsive means for periodically starting a discharge in said gas-filled discharge device to thereby discharge said condensers.

13. A linear time axis generator comprising two condensers connected in series with the common terminal of said condensers placed at a fixed potential, means including a constant current device and a direct current source in series with said condensers for charging said condensers, said constant current device comprising an electron discharge device having a cathode, an anode, a control grid, a screen grid, and a suppressor grid, means for fixing the biasing potentials of said screen and suppressor grids with respect to that of said control grid, means including said direct current source for maintaining a flow of current in said discharge device, means including a resistance in circuit between said cathode and said control grid to control the bias on said grid to thereby keep the flow of current through said device substantially constant, a gas-filled electron discharge device having an input and an output circuit, said output circuit including said condensers, and signal responsive means for periodically starting a discharge in said gas-filled discharge device to thereby discharge said condensers.

FRANK R. NORTON.
